DESIGN FOR EMBLEMATIC BADGE OR SIMILAR ARTICLE

Frank A. Schlesinger, Thornwood, N. Y.

Application January 18, 1934, Serial No. 50,442

Term of patent 14 years

To all whom it may concern:

Be it known that I, Frank A. Schlesinger, a citizen of the United States, residing in Thornwood, in the county of Westchester and State of New York, have invented a new, original, and ornamental Design for Emblemsatic Badge or Similar Article, of which the following is a specification, reference being had to the accompanying drawing, forming a part hereof.

The figure in the drawing shows a plan view of an emblematic badge or similar article embodying my design, in which a side view of an automobile is shown within a field slightly larger forming a contrasting background, with a border of dominating appearance around and in contrasting color with the field. This design is made

on the surface of material such as woven fabric which has a uniform and relatively slight thickness.

The design consists of the combination of elements above described embroidered in contrasting colors on a chevron-like fabric.

The design comprises essentially a side view of an automobile in a circular field of contrasting and relatively darker color and a circular border of relatively lighter color.

I claim:

The ornamental design for emblematic badge or similar article as shown and described.

Signed at New York, New York, this 3rd day of January, 1934.

FRANK A. SCHLESINGER.
